US00D617330S

(12) **United States Design Patent**
Gloscia et al.

(10) **Patent No.:** **US D617,330 S**
(45) **Date of Patent:** ** *Jun. 8, 2010

(54) **MOBILE COMPUTING DEVICE**

D479,234 S 9/2003 Tanaka et al.

(75) Inventors: **Richard Gloscia**, Santa Clara, CA (US);
Chrome Cebe, San Jose, CA (US)

(Continued)

(73) Assignee: **Palm, Inc.**, Sunnyvale, CA (US)

FOREIGN PATENT DOCUMENTS

(**) Term: **14 Years**

WO DM/054225 2/2000

(57) **CLAIM**

The ornamental design for a mobile computing device, as shown and described.

DESCRIPTION

FIG. 1 is a front view of a first embodiment of a mobile computing device;

FIG. 2 is a front view of a second embodiment thereof;

FIG. 3 is a front view of a third embodiment; and,

FIG. 4 is a front view of a fourth embodiment.

The broken line showing of a mobile computing device is included for the purpose of illustrating environmental structure and forms no part of the claimed design.

1 Claim, 4 Drawing Sheets
